UNITED STATES PATENT OFFICE

WILLIAM FLETCHER, OF LONDON, ENGLAND, AND ALBERT OGWIN LEWIS, OF GLAIS,
WALES

HAIR WAVER

Application filed September 2, 1931. Serial No. 560,714.

This invention relates to hair wavers of the kind comprising a resilient mesh-work which is fitted over the head to form the hair into waves. A disadvantage with this kind of waver is that, in use, the mesh-work is subjected to an uneven tension and as a result, certain portions of the mesh-work fit the head too loosely and other portions fit too tightly, the latter portions causing discomfort to the wearer and the whole irregular fitting of the mesh-work impairing the waving properties of the device. The object of the present invention is to overcome these disadvantages. A further object of the invention is to facilitate and decrease the cost of manufacture.

The hair waver according to this invention comprises a resilient mesh-work including a single length of a resilient element, such for example, as an elastic cord and a plurality of resilient hair engaging elements, each of which is provided with a loop at each end through which the said elastic cord is threaded, means for extending the mesh-work about the head and means for retaining said mesh-work in operative position on the head.

An embodiment of the invention is illustrated in the accompanying drawing, wherein:

Fig. 1 shows the waver in position on the head.

Fig. 2 shows details, on an enlarged scale, of the back of the waver.

Fig. 3 is a diagrammatic view illustrating the relation of the head, the hair and the waver when the waver is in extended position during fitting.

Fig. 4 is a similar view to Fig. 3, but with the waver in operative position.

Fig. 5 is a part sectional plan of one of the resilient members associated with the elastic cord to form the resilient mesh-work; and

Fig. 6 is a part sectional side elevation of the resilient member illustrated in Fig. 5.

Referring to the drawing, the waver comprises a resilient mesh-work including a single length of elastic cord 1 and a plurality of hair engaging elements 2, each of which is provided with a loop 3 at each end. The said elements 2, which are arranged longitudi-

nally on the head, are preferably constructed as hereinafter described.

The cord 1 is threaded through the loops 3, the portions of the cord passing through the loops at the front and back ends of the elements 2 constitute a front head spanning member 4 and a rear head spanning member 5, respectively, the ends of said members extending downwardly to form a fitting loop 6 on each side of the wearer's head to which ribbons 7 are connected. The fitting loops or the ribbons connected thereto are adapted to be held by the wearer to extend the mesh-work about the head during fitting. The cord 1 is looped at the back as shown in Fig. 2, to form two transverse connecting elements 8, 9, serving to connect the ends or lower portions of the rear head spanning member and to position the waver on the head. It will be seen from Fig. 2 that one end of the rear head spanning member, the right hand end being shown in the drawing, passes through two loops 3¹ on the two lowermost hair engaging elements on one side of the waver and is extended transversely across the back of the device to constitute one of the transverse connecting elements. The cord is then secured, by passing it through two loops 3¹¹ on the two lowermost hair engaging elements on the opposed side of the device, for a part of its length, to the other end of the said rear head spanning member, the cord then returning across the back of the device to constitute the second transverse connecting element, after which the cord continues down through the two loops 3¹ to form one of the fitting loops and the front head spanning member.

Preferably, a knot 12 is formed in one end of the back head spanning member (see Fig. 2) above the lowermost hair engaging member. Another knot 13 is formed at the end of the upper transverse connecting element above and adjacent the lowermost hair engaging member on the other end of the back head spanning member. These knots which are too large to pass through the loops on the hair engaging elements, are adapted to engage the said loops and serve as stops to enable a symmetrical adjustment of the various lengths of the cord to be obtained.

The size of the loops 3 at the ends of re-

silient members 2, is preferably such that although the members are frictionally held in place on the elastic cord 1, the members can be displaced along the cord to adjust their position, by slightly extending the cord to reduce its diameter.

In the preferred form of the resilient hair engaging members (see Figs. 5 and 6), the members each comprise a flat resilient strip 14 of metal, celluloid or other suitable material having the ends bent over to form the loops 3. The flat strip 14 is enclosed within a rubber or the like sheath 15 having a ribbed surface in order to ensure ready engagement with the hair. The ends of the sheath 15 abut against the head spanning members so as to position, or assist in positioning, the resilient members 2 on the head spanning members.

It will be understood that a coil spring or other suitable resilient element may be used in place of the elastic cord 1.

When using the waver, the hair is damped and the resilient meshwork is stretched over the head, as illustrated in Fig. 3, by pulling on the fitting loops 6 or the ribbons 7, the head being diagrammatically illustrated by the reference 16 and the hair by reference 17. After sufficient extension has been produced, the meshwork is released and the hair is waved by the action of the resilient members 2 engaging therewith, as illustrated in Fig. 4. The hair is allowed to dry with the appliance in this position and, if necessary, the appliance can be worn without discomfort during sleep.

In order to retain the waves in the hair for a considerable time, the hair may be sprayed with a setting lotion of known kind, or, alternatively means may be provided whereby the resilient members 2 can be heated either by electricity or other means. When heated by electricity the resilient members 2 are constructed of insulating material and are insulated from one another and from the head of the wearer as necessary.

The employment of a single length of a resilient element in the construction of the resilient meshwork, ensures an even tension being obtained throughout the meshwork and enables the meshwork to be readily adjusted to individual requirements, and, further, the waver is more readily manufactured and production costs are reduced, in so far as it is not necessary to construct the meshwork from a plurality of lengths of material which have to be secured one to the other.

We claim:—

1. A hair waver comprising a resilient meshwork including a single length of an elastic element having portions forming front and rear head spanning members and a plurality of hair engaging elements, each of which is provided with a loop at each end through which the head spanning members

of said elastic element is threaded, means for extending the meshwork about the head and means for retaining said meshwork in operative position on the head.

2. A hair waver comprising a resilient meshwork, including a single length of elastic cord and a plurality of longitudinally arranged hair engaging elements, each of which is provided with a loop at each end, the said elastic cord comprising a back head spanning member and a front head spanning member, which are threaded respectively through the back and front loops of the hair engaging elements, the said cord being looped at the back to constitute two transverse connecting elements, means for extending the meshwork about the head and means for retaining said meshwork in operative position on the head.

3. A hair waver comprising a resilient meshwork, including a single length of elastic cord and a plurality of longitudinally arranged hair engaging elements, each of which is provided with a loop at each end, the said elastic cord comprising a back head spanning member and a front head spanning member which are threaded respectively through the back and front loops of the hair engaging elements, the said cord being extended from one end of the back head spanning member to the other end thereof to constitute a transverse connecting element, the cord being passed through a loop on the lowermost hair engaging element on the last mentioned end of the back head spanning member and returned to the first mentioned end to constitute a second transverse connecting element from which end the cord is continued to form the front head spanning member, means for extending the resilient meshwork about the head and means for retaining said meshwork in operative position on the head.
